WELL PUMP

William Fred Cox, Shreveport, La.

Original application August 29, 1935, Serial No. 38,449. Divided and this application October 31, 1936, Serial No. 108,658

4 Claims. (Cl. 103—221)

This invention relates to improvements in well pumping apparatus and, particularly, to oil well pumps of the type wherein the space between the pump and well wall or casing is sealed at a point along the exterior surface of the pump structure. The sealing of this space is accomplished by means commonly referred to as a packer, which usually comprises a radially expandable sleeve carried by the pump and a tubular mandrel which, under certain conditions, can be moved to a position within the sleeve to expand the latter into sealing engagement with the well casing. In the event the pump is to be withdrawn from the well for repairs, cleaning out the well, or the like, it is necessary to disengage the mandrel from the sleeve, usually by raising the mandrel in the well hole. However, in casing pumps, i. e., that type of pump which flows the liquid through the well casing to the surface of the ground, the liquid above the seal or packer exerts a tremendous pressure on the packer mandrel and to relieve this pressure preliminary to withdrawing said mandrel from the packer sleeve, means are provided for by-passing the liquid from above the packer to a point below the packer. Preferably, one or more by-pass ports are provided in the pump cylinder wall and the flow of liquid through said ports is controlled by a valve which, in the present invention, is yieldingly urged toward its port-closing position by a spring. When said valve is moved toward its open position, said spring will, of course, be compressed and the primary object of the present invention is to provide means for limiting the compression of said spring, or preventing said spring going solid whereby the life thereof is materially prolonged. Briefly, therefore, the invention may be said to contemplate the provision of means for by-passing liquid from above the well sealing devices, such means comprising a spring seated valve for the by-pass or drain port and means for preventing excessive compression of said spring.

With these and other objects in view, the invention consists in certain details of construction and combinations and arrangements of parts, all as will hereinafter be more fully described and the novel features thereof particularly pointed out in the appended claims.

In the accompanying drawing—

Figure 1 is a vertical cross-sectional view through the well casing and a portion of a pump mechanism illustrating the preferred embodiment of the present invention, the parts being in the position they occupy as the pump is lowered into the well; and

Fig. 2 is a similar view, illustrating the essential elements of the present invention, in the positions they occupy, when the pump is operatively positioned in the well.

The present application is a division of applicant's co-pending application Serial No. 38,449, wherein the pump structure proper illustrated in the present instance is more fully disclosed and claimed. The present invention can, of course, be utilized in various constructions of pumps but in the preferred pump structure illustrated, there is an upper conical member or hollow mandrel 31, and a lower cylindrical member 32 which is, in effect, an extension of the pump cylinder or working barrel 41, being connected to the working barrel proper by a tubular coupling member 32^b. The conical outer surface of mandrel 31 tapers downwardly toward the cylindrical surface of member 32 and these surfaces are coaxially arranged. The bore of cylindrical member 32 opens into the interior of the hollow mandrel 31, the latter being provided with a number of openings 33, through which oil passing upwardly from the pump cylinder will flow into the well casing indicated at 20. Mandrel 31 is provided with a bore 34 for the accommodation of the lower end of the sucker rod string 45 which extends from within the pump cylinder to a point above the ground surface whereby the pump may be raised and lowered in the well and the pump piston 43 reciprocated in the pump cylinder. Of course, other means, such as cables, etc., may be utilized for raising and lowering the pump and actuating the piston, if desired. Slidably axially on the working barrel or cylinder of the pump is a cylindrical slide 35 to the lower end of which there is connected what is commonly called the shell of the pump. The shell is indicated at 21 and at the upper end of said slide 35 there is secured an expandable sleeve 37 of rubber or some similar substance, the lower end of said sleeve being inferiorly grooved and receiving an annular flange 38 on the upper end of the slide whereby said expandable sleeve is firmly secured on the slide. Downward movement of slide 35 on the pump cylinder is limited by a stop 41^a on the pump barrel, said stop preferably being formed by the collar by which the cylindrical member 32 is secured to coupling member 32^b. Said collar 41^a is adapted to be engaged by the lower end of the slide 35 to arrest its downward movement relatively to the pump cylinder. At the lower end of the pump cylinder, there is a standing valve 42 which may be of any desired construction, and the pump piston, which may also be of any well-

known type, carries the traveling valve 43^a. As is well known, reciprocation of the sucker rods and piston causes oil to first be sucked through standing valve 42 upon the up stroke of the piston, which oil, on the downward stroke of the piston unseats and passes traveling valve 43^a.

Various means, well known in the art, may be provided for supporting the pump proper at the desired pumping elevation in the well hole, but 10 as these means form no part of the present invention, they are not shown or described. Suffice it to say that the pump is supported on the sucker rod 45 while it is being lowered into the well, but when the shell 21 comes to rest in the 15 well, the working barrel and the mandrel 31 continue downwardly until the mandrel enters and expands the sleeve 37 into sealing engagement with the well casing 20.

Thus, with the pump barrel fixed and sealed in 20 the well, by continuing the downward movement of the sucker rod, the piston will move to its working position with the pump barrel and, as will be later described, the by-pass will be sealed off, so that the pump is ready for operation. Should 25 it be desirable to remove the pump, or to adjust its position in the well, it is only necessary to open the by-pass, as will be later described, in order to relieve the pressures above the mandrel 31, after 30 which the sucker rod is raised to remove mandrel 31 from the packing member 37.

As before mentioned, it is quite advantageous to by-pass oil from above the mandrel 31 when it is desired to raise the pump, because the pressures imposed upon the mandrel, particularly in 35 the deep wells of today, are such that it is quite difficult to break out the sealing or packing element so long as those pressures exist and the force required may be great enough to cause breaking of the sucker rod string. The particular 40 arrangements for by-passing the oil above the mandrel are shown and described in detail in my copending application, Serial No. 38,449. Described briefly, these means consist of ports 90 in the cylindrical extension 32 of the pump barrel and ports 91 in member 35 and a sliding tubular valve 100 carried on the sucker rod 35 for controlling the flow of oil from within the pump to the exterior thereof. As shown in Fig. 2, when 45 the pump is in pumping position, a coil spring 92 surrounding the sucker rod and interposed between the upper end of the mandrel 31 and sliding valve 100 holds said valve depressed so that the cups 101 at the upper end of the valve and the cups 102 at the lower end of the valve prevent 50 oil in the pump cylinder or in the interior of the mandrel gaining access to the ports 90, 91. In other words, oil drawn into the pump barrel will be forced upward through the tubular valve or sleeve 100 and into the interior of the mandrel 55 and then through openings 33 into casing 20. However, if it is desired to pull the pump, the sucker rod is raised until collar 14^b engages valve 100 and elevates it to a point where the cups 101 will be moved out of the cylinder 32, under which 60 conditions, oil above the packing elements will drain back down through the annular space between the tubular sleeve 100 and cylinder 32 and through ports 90, 91, into the space between the 65 pump shell 21 and well casing 20. Although not essential, it is highly desirable to provide a spring 92 for the purpose of depressing, or seating, the tubular valve 100. However, when the pump is being lowered or raised, the entire weight thereof is carried on the sucker rod and if the spring 92

should be placed under excessive compression, it would be practically destroyed. To overcome this difficulty, collar 14^b on the sucker rod which engages the cross member 100^a of the slide valve is so positioned with respect to the upper end of sleeve 52 on the sucker rod that the latter will come into contact with the bushing 34^a in the mandrel head before spring 92 can go solid. In other words, the sleeve 52 which is fast on the sucker rod forms an enlargement adapted to function as a stop for limiting the compression of spring 92 by abutting against bushing 34^a before said spring goes solid. In this way, damage to the spring by excessive pressures, particularly during the lowering and raising of the pump, is 15 absolutely precluded.

What I claim is:

1. In an oil well pump, a pump cylinder, means for sealing off the well at a point along the cylinder wall, said cylinder having a port therein for by-passing liquid from above said seal to a point below the seal, a slide valve for said port, a sucker rod, an enlargement on said rod engageable with a member carried by said cylinder for raising said cylinder, a coil spring on said rod for moving said slide valve to port-closing position, one end of said spring engaging said member, and means on said sucker rod for moving said valve from its port-closing position against the pressure of said spring, the spring, the spacing of said last-mentioned means and said enlargement axially of the rod being such that said enlargement will contact said member in advance of said coil spring going solid. 30

2. In an oil well pump, a pump cylinder, means for sealing off the well at a point along the cylinder wall, said cylinder having a port therein for by-passing liquid from above said seal to a point below the seal, a slide valve for said port, a sucker rod, an enlargement on said rod engageable with a member carried by said cylinder for raising said cylinder, a coil spring on said rod for moving said slide valve to port-closing position, and means for moving said valve from its port-closing position against the pressure of said spring, the spacing of said last-mentioned means and said enlargement axially of the rod being such that said enlargement will contact said member in advance of said coil spring going solid. 35

3. In an oil well pump, a pump cylinder, means for sealing off the well at a point along the cylinder wall, said cylinder having a port therein for by-passing liquid from above said seal to a point below the seal, a sucker rod, an abutment on said rod engageable against a portion of the pump structure for supporting the pump in the well, a slide valve for controlling flow of liquid through said port, a spring urging said valve toward its port-closing position, and means operable by movement of said rod longitudinally of the pump cylinder for moving said valve toward its port-opening position against the pressure of said spring, the compression of said spring being limited by the engagement of said abutment with said pump structure. 50

4. In an oil well pump, a pump cylinder having a drain port in the wall thereof, a valve controlling the flow of liquid through said port, a spring for urging said valve toward its port-closing position, means for opening said valve against the pressure of said spring, and means for limiting compression of said spring when said valve is moved toward its open position. 70
